(No Model.)

F. A. WELLER & A. F. RIETZEL.
ELECTRIC SWITCH.

No. 398,560.

Patented Feb. 26, 1889.

UNITED STATES PATENT OFFICE.

FRANKLIN A. WELLER AND ADOLPH F. RIETZEL, OF LYNN, MASSACHUSETTS.

ELECTRIC SWITCH

SPECIFICATION forming part of Letters Patent No. 398,560, dated February 26, 1889.

Application filed December 12, 1888. Serial No. 293,374. (No model.)

To all whom it may concern:

Be it known that we, FRANKLIN A. WELLER and ADOLPH F. RIETZEL, both of Lynn, in the county of Essex, State of Massachusetts, 5 have invented a certain new and useful Improvement in Electric Switches, of which the following is a description sufficiently full, clear, and exact to enable any person skilled in the art or science to which said invention 10 appertains to make and use the same, reference being had to the accompanying drawings, forming part of this specification, in which—

Figure 1 is a top plan view of our improved 15 switch, the cap being removed; Fig. 2, a vertical transverse section, the cap being in position; Fig. 3, a like view taken on line $x-x$ in Fig. 1, and Figs. 4 and 5 sectional views illustrating details of construction.

Like letters and figures of reference indicate corresponding parts in the different figures of the drawings.

Our invention relates especially to that 20 class of electrical switches which are ordinarily known as "double-pole" switches, and are particularly adapted for use with electric-light wires; and it consists in certain novel features, as hereinafter fully set forth and claimed, the object being to produce a simpler, 25 cheaper, and more effective device of this character than is now in ordinary use.

The nature and operation of the improvement will be readily understood by all conversant with such matters from the following 30 explanation.

In the drawings, A represents the body or 35 table of the switch, and B the case. The table consists of a circular wooden plate chambered at b on its under side, and provided with 40 screw-holes d, by means of which it may be readily attached to a wall or other convenient position. A metallic plate, C, is secured to the face of the table by screws f, and formed integral with said plate is a vertically-arranged tube, g, which projects downward 45 through said table, as shown in Figs. 2 and 3. The front wall of the tube g is cut away at h above the plate C, and fitted to slide vertically 50 therein is a rod, i. Secured to the upper end of the rod i there is a plate, k, pro-

vided with two forwardly-projecting arms, l m, situated, respectively, at the ends of said plate, the arm l being farther from the table A than the arm m, as shown in Fig. 3: A horizontally-arranged wooden bar, D, is centrally secured on the plate k by a bolt, q, and is provided at each end with a slot, 12, and screw 22, forming clamps, in each of which a downwardly-projecting metallic rod or plunger, p, is adjustably secured. A vertically-disposed standard, r, is secured to the plate C, so that its top projects between the arms l m of the plate k. On the upper end of the standard r is formed a diagonally-arranged cam, H, having an upper face or track, t, and a lower face 65 or track, v.

A lever, K, is pivoted at w to the forward end of the plate C so that it will swing horizontally, said lever being provided on its outer end with a handle, L, and having its inner end projecting into a horizontal guide slot or groove, y, formed at the base of the standard r. A stop, z, is disposed at each side of the plate C to engage said lever and prevent it from being swung too far on its pivot. 75 A horizontally-arranged stiff flat spring, P, is secured at one end to the lever K by a bolt, 15, upwardly-projecting studs 25 preventing the spring from moving laterally thereon.

The free end of the spring P is extended 80 longitudinally over the lever K, its extreme point being in position to engage the tracks v of the cam H when said lever is moved.

Two ordinary brass poles or connectors, 35, are secured to the face of the table A equidistant from one end of the bar D, said connectors being provided with a slot, 45, and screw 55 for securing the conducting-wire 85 therein in the usual manner. Two similar connectors, 65, are secured to the table equidistant from the opposite end of the bar D.

A plate, 75, of soft copper, (see Fig. 4,) is disposed on the table A in contact with each pole 35 and 65, the plates of companion poles being extended toward each other and their free ends 85 flattened and turned vertically upward, forming sockets for the plungers p when depressed, as hereinafter described. A spring, 95, composed of phosphor-bronze, is secured to the top of each plate 75, its free 90 95 100

end bearing against the end 85 of said plate and tending to force it toward its companion plate, (see Fig. 4,) the purpose of said springs being to render certain the contact between 5 the soft-copper plates and the plungers *p* when in use.

The upper end of the rod *i* is slotted vertically on its rear side, as shown at 14 in Fig. 2, and a screw, 24, projects through the tube 10 *g* into said slot to serve as a stop for preventing said rod from being elevated too far.

A vertically-arranged spring, 34, (see Fig. 5,) is secured to the plate *r* in position to engage the bar *D* and prevent it from being accidentally moved from the position into which 15 it may be thrown.

The cap *B* is designed to inclose the device on the table *A*, and is provided with an opening, 44, through which the handle *L* of the 20 lever *K* projects, said cap being held in position by a screw, 54, in the upper end of the tube *g*, which projects through a slot in said cap.

The wires *N* *M* pass upward through holes 25 64 in the table *A*, their ends being respectively secured in the poles 35 and 65, as shown in Fig. 1.

In the use of our improvement, the bar *D* being elevated, as shown in Figs. 2 and 3, the 30 circuit is broken. If it is desired to close or complete the circuit, the handle of the lever *K* is moved from right to left or into the position shown by the dotted lines 13 in Fig. 1. This causes the free end of the spring *P* to be 35 forced upward on the upper face, *t*, of the cam *H*, as shown by dotted lines 23 in Fig. 2. When the spring leaves or passes the upper end of said track, it strikes the arm *m* of the plate *k* and forces the rod *i* downward in the 40 tube *g*, the plungers *p* being at the same time forced between the ends 85 of the soft-copper plate 75, and connection thus made between the companion poles. To break the circuit the lever *K* is moved in the opposite direction, 45 causing the ends of the spring *P* to follow the track *v* of the cam, as shown by dotted lines 33 in Fig. 2, and when it leaves the lower end of said track to strike the under side of the arm *l* of the plate *k*. This forces the rod *i* 50 upward in the tube and disconnects the plungers *p* from the copper plates 85.

It will be seen that the screw 24 prevents the rod *i* from being thrown too far upward by the spring.

55 By using the phosphor-bronze springs 95 the wear of the plungers upon the soft-copper plates is in a great degree compensated for and the contact between said plungers and plates rendered perfect. Moreover, the 60 plungers, being disposed in the slots 12, may be adjusted vertically, and their contact with the sockets rendered simultaneous, thus preventing the action of the "spark" from being greater upon one than the other of said 65 plungers.

Having thus explained our invention, what we claim is—

1. In a switch of the character described, the combination of a table provided with poles, a rod bearing metallic plungers and fitted to 70 slide in said table, metallic sockets for said plungers in contact with companion poles, a pivoted lever provided with a flat spring, a cam provided with two faces or tracks for distending said spring when the lever is moved, 75 and arms on said rod for engaging the spring when it leaves said tracks, substantially as set forth.

2. In a switch of the character described, the combination of a table provided with poles, 80 a rod fitted to slide in said table and provided with a plate having arms, a bar on said plate provided with metallic plungers, metallic plates in contact with companion poles and forming sockets for said plungers, a pivoted 85 lever provided with a flat spring, and a cam for distending said spring when the lever is moved, whereby it will strike one of said arms when returning to its normal position after leaving said cam, substantially as and 90 for the purpose specified.

3. In a switch of the character described, the combination of a table provided with poles, a bed-plate provided with a tube, a rod fitted 95 to slide therein, a plate on said rod provided with arms, a bar secured to said rod and bearing metallic plungers, metallic plates in contact with companion poles and forming sockets for said plungers, a pivoted lever provided with a flat spring, and a cam on said bed-plate for distending said spring, whereby it 100 may be caused to strike said arms and actuate the plungers, substantially as set forth.

4. In a switch of the character described, the combination of the table *A*, provided with 105 the poles 35 and 65, the rod *i*, fitted to slide in said table and provided with the plate *k*, having the arms *l* *m*, the bar *D*, provided with the plungers *p*, the plates 75 in contact with said poles and forming sockets for said plungers, and mechanism for engaging said arms 110 and actuating said plungers, substantially as and for the purpose set forth.

5. In a switch of the character described, the combination of a table provided with poles, 115 a bed-plate having a vertical tube, a rod fitted to slide in said tube, a plate on said rod having outwardly-projecting arms, a bar provided with metallic plungers and secured to said plate, a soft-copper plate in contact with each 120 pole, companion plates forming sockets for the plungers, a pivoted lever provided with a flat spring, and a cam having two faces for distending said spring when said lever is moved, whereby it is caused to strike an arm 125 of said plunger-plate as it leaves the cam, substantially as and for the purpose set forth.

FRANKLIN A. WELLER.
